CLAIM

The ornamental design for a convertible carry container and placemat, as shown and described.

DESCRIPTION

FIG. 1 is a front, top perspective view of a combination convertible carry container and placemat showing my new design in a closed position;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a bottom perspective view of the combination convertible carry container and placemat showing my new design in an opened position;

FIG. 9 is a top perspective view thereof;

FIG. 10 is a top plan view thereof;

FIG. 11 is a bottom plan view thereof;

FIG. 12 is an enlarged view of the portion 12 encircled in FIG. 8; and,

FIG. 13 is an enlarged view of the portion 13 encircled in FIG. 11.

The broken lines in the drawings illustrate stitching that forms part of the claimed design.

The broken lines in FIGS. 8 and 11-13 encircling portions of the claimed design depict the boundaries of the enlargements and form no part of the claimed design.

A characteristic feature of the design resides in the flat bottom shape of the two bottle-holding pockets on the left and right sides of the combination convertible carry container and placemat.
